(57) CLAIM

The ornamental design for an artificial lash extension, as shown and described.

DESCRIPTION

FIG. 1 is a top perspective view of an artificial lash extension, showing my new design;

FIG. 2 is a bottom perspective view thereof;

FIG. 3 is a left side perspective view thereof;

FIG. 4 is a right side perspective view thereof;

FIG. 5 is a left side view thereof;

FIG. 6 is a right side view thereof; and,

FIG. 7 is a top view thereof.

The broken lines and the grayed areas in the photographs depicting the base of the artificial lash extension are for illustrative purposes only and form no part of the claimed design.

1 Claim, 7 Drawing Sheets
